United States Patent Office.

GEORGE M. GUILD, OF BOSTON, MASSACHUSETTS.

Letters Patent No. 78,276, dated May 26, 1868.

IMPROVEMENT IN SOUNDING-BOARD FOR PIANOS.

The Schedule referred to in these Letters Patent and making part of the same.

TO ALL WHOM IT MAY CONCERN:

Be it known that I, GEORGE M. GUILD, of Boston, in the county of Suffolk, and State of Massachusetts, have invented an Improvement in Sounding-Boards for Piano-Fortes; and I do hereby declare that the following, taken in connection with the drawings which accompany and form part of this specification, is a description of my invention sufficient to enable those skilled in the art to practise it.

My invention relates to the construction of a sounding-board for piano-fortes, with reference to the employment of a thin board, with such provision for rigidifying it as shall not impair its vibrating quality.

As ordinarily made, sounding-boards are quite thick, and have wooden bars or ribs running right angularly across, and glued to them, to give the requisite strength, and they have been made of two thicknesses of boarding, (of the size of the sounding-board,) glued together crosswise of the grain of the woods.

My invention consists in strengthening a sounding-board by two series of ribs, or a main and an auxiliary series, the ribs of the main series, preferably, running diagonally across the under surface of the board, and the ribs of the auxiliary series running across the main ribs, thus rigidifying and strengthening the board in each direction, and admitting of a very thin board, having great freedom of vibration.

The drawing represents a sounding-board embodying my improvement.

A shows the under side of the board.

B is an end view of it.

C is a section on the line x x.

a denotes the upper surface of the board, to which is fixed the string-bridge b.

On the under surface of the board are the main ribs or braces c, each made of a thin strip of board, which is laid diagonally across the surface of the board a, and is glued thereto. The ends of these ribs (excepting at the large end of the sounding-board) project under the edge rails d. These ribs run crosswise of the grain of the board a, and are made quite thin, so as not to impair the vibrations of the board; and to keep them and the board from springing, I cross their outer surfaces with auxiliary and, preferably, thicker wooden ribs or bars, e, which are glued to the surfaces of the main ribs c, where they cross, and the ends of these bars may also extend under the edge rails d.

The specific arrangement or form of the ribs c and e may differ from what is shown in the drawings. They may be wide or narrow, more or less numerous, and at greater or less distance apart, the essential feature of my invention consisting broadly in the employment of auxiliary ribs, crossing and confined to the main ribs.

It will be obvious that by this construction the sounding-board may be made very thin and sonorous, the proper strength and rigidity being secured by the double series of bars, and that the sounding-board will be thus made capable of quick vibration.

I claim, in combination with a sounding-board, and the main supporting-ribs c thereof, the auxiliary ribs e, crossing and secured to the ribs c, substantially as shown and described.
